United States Patent Office.

HALL COLBY, OF NEW YORK, N. Y., ASSIGNOR TO HIMSELF AND GEORGE G. COLBY, OF WASHINGTON, DISTRICT OF COLUMBIA.

Letters Patent No. 100,119, dated February 22, 1870.

IMPROVEMENT IN ALTITUDE INSTRUMENT.

The Schedule referred to in these Letters Patent and making part of the same.

To all whom it may concern:

Be it known that I, HALL COLBY, of the city and county of New York, in the State of New York, have invented a new Horizon Instrument; and I do hereby declare that the following is a full, clear, and exact description thereof, reference being had to the accompanying drawings making part of this specification, in which—

Figure 1, plate 1, is a front view of the improved instrument.

Figure 2, plate 1, is a sectional view of the instrument, showing the stop-lock and catch.

Figure 3, plate 2, is a view of the back of the instrument.

Figure 4, plate 2, is a vertical section, taken transversely through the center of the instrument.

Similar letters of reference indicate corresponding parts in the several figures.

The object of this invention is to construct an instrument which shall be simple and readily adjustable, and by means of which a correct altitude of the sun, moon, or stars, or the altitude of terrestrial objects can be readily determined, notwithstanding the natural horizon may be obscured.

My invention is especially adapted for finding the correct position of a ship at sea, when other instruments cannot be used, on account of a fog or darkness obscuring the horizon. To this end I have adapted the improved instrument to indicate both altitude and zenith at the same time, and to do away with the usual corrections, such as dip, parallax, and refraction, and semi-diameter. I have also so constructed the instrument that it can be readily tested for determining its accuracy at any time, as will be hereinafter explained.

The following description will enable others skilled in the art to understand my improved instrument.

In the accompanying drawings—

A represents what I denominate a graduated double-vernier balance, which is suspended from an axis, c, so as to swing freely, and which is graduated at $g' g$, so as to form a double-vernier, including an arc of ninety degrees. This double-vernier balance is suspended from bearings, which are applied to the frame G of the instrument, at the back of which frame is a handle, J, by which the instrument is held while taking an observation.

The frame G has a flange, G', formed on its perimeter, the face of which is marked off, so as to present two scales ranging on each side of the cypher or nadir mark to 90° or more, thus giving an arc of 180° or more, representing by the aid of the double-vernier arc, altitude and zenith distance.

This graduated arc is surmounted by a horizon-plate or level, b, which is in a plane at right angles to a plane intersecting the axis c and cypher-mark on the arc of 180° .

This horizon-plate b is provided with a spirit level, P, shown in fig. 4, which is used for determining the accuracy of the instrument in the following manner:

If, when the bubble of the spirit level indicates that the plate b is horizontal, the arrow on the face of the lower limb of the double-vernier balance points to the cypher on the arc of 180° , as indicated in fig. 1, then it is known that the instrument is properly adjusted for observation.

On the horizon-plate b I secure a telescope, which is composed of two tubular sections $a a^2$, applied one at each extremity of the said plate, and adjusted so that their axes coincide and are in a plane parallel with the plate b. The tubes $a a^2$ have no lenses in them, but are provided with crossed wires and fine-sighting-plates. The cross-wires are applied in the tube a^2 , and the sighting-plates are applied in the tube a.

By thus constructing the telescope of two separated sections, an object can be more readily found than in any other manner.

The lower limb of the double-vernier balance A is loaded in a suitable manner, so as to hang plumb from the axis c; and to the inner or back side of this limb a grooved pulley, d', is applied, around which is passed a cord, e. The ends of this cord are attached to bow-strings d d, which are of equal tension, and which are secured to the frame G, on opposite sides of the axis c, as shown in fig. 1.

The tension which is thus produced will prevent the double-vernier balance from being too sensitive to vibration, without interfering with its accuracy as a balanced vernier in the use of the instrument.

Beneath the double-vernier balance A and pivoted to a stud, o, is a lever, C, carrying on one end a bevelled locking-tooth, n, which passes through and is guided by the bottom of the frame G, as shown in fig. 2.

A spring, s, is applied to frame G, so as to act upon C, and press the tooth n upwardly and lock the frame and vernier balance, and thus allow the angles which have been found by observation through the telescope to be read off on the scale $f' f' g' g$.

The lever and tooth are set by means of a trigger, h, which is applied on the end of a spring, i, as shown in fig. 2. When the lever C is held up by the trigger, as shown in fig. 2, the vernier A and frame G are released from tooth n, and the instrument is adjusted for use.

It will be seen from the above description that the improved instrument has a geocentric balance with an arc of 90° , and with two verniers 90° apart, so arranged that the altitude vernier rests at the center or nadir, 0, of the arc of 180° , when the zenith vernier points to the 90° mark (or plane of the telescope) on the arc G', by which means the correct altitude can be taken of the sun, moon, planets, or stars, or of any elevated terrestrial object.

It will also be seen that the double-vernier balance has a movement in space of 90° , and that an observation will always indicate upon the instrument, (so that it can be plainly read off,) the altitude and zenith distance of the object observed, from which the position of the observer or ship can be ascertained with sufficient accuracy for all practical purposes.

The vernier *g* points to the altitude scale *f*, and the vernier *g'* to the zenith scale *f'*. The scales or divisions on the vernier arc indicate degrees and half degrees, by which the vernier reads to miles, (or minutes.) Thus, thirty divisions on a vernier scale cover twenty-nine divisions on the arc of 180° .

Having described my invention,

What I claim as new, and desire to secure by Letters Patent, is—

1. An instrument for determining at the same time both the altitude and zenith distance of celestial or terrestrial objects, which consists of the arc *G* of 180° , a level, *P*, a horizon-plate, *b*, telescope *a* a' , and a double-vernier balance, *A*, in combination with a stop-lock or catch, substantially as described.

2. The combination with the vernier balance *A* of a tension-device, consisting of tension-springs *d* *d'*, cord *e*, and a pulley, *d'*, substantially as described.
